PICKER

Walter E. Segl, Wilmington, Del., assignor to Hercules Powder Company, Wilmington, Del., a corporation of Delaware

Application April 26, 1945, Serial No. 590,493

2 Claims. (Cl. 19—80)

1

This invention relates to a picker, and more particularly, to a device for picking a mass of fibrous material.

In the art of picking fibrous materials, such as cotton, wool, hair, pulp, synthetic fibers, and the like, it is known to pass the material through either horizontal or vertical drums of cylindrical or conical shape provided internally with revolving beater arms, sometimes carrying metallic teeth or with a revolving picker roll provided with radially extending picker teeth or pins. There are other pickers for fibrous materials comprising continuous belts provided with wire teeth which move across the discharge end of a continuous conveyor carrying the fibrous mass.

Pickers of the drum type provided with revolving picker rolls carrying extending picker teeth or pins, which are known to the art, have not been entirely satisfactory when used for picking damp, compact, purified cotton linters, to adapt the short fiber material for efficient drying in a suitable drying chamber. There are still other disadvantages of the drum-type picker provided with conventional revolving beater arms carrying teeth secured to the ends of said beater arms, that are not inherent in the cylindrical rotor-type picker roll.

The picking of a mass of damp, purified cotton linters, still containing considerable water, for the purpose of opening it up so as to obtain perfectly uniform drying in a drying chamber, while at the same time maintaining its high degree of purity without contamination with material from the picker, presents a number of problems. The clearance between the picker pins or teeth of the rotor and the drum housing must be small on account of the short length of the fibers; heavy and strong construction must be employed because of the high resistance to compression of the damp and compact mass of short fibers; the small clearance between the ends of the picker teeth and the housing, with the great resistance of the compact fibrous mass, requires rigid securing of the pins to the rotor with no chance of being gradually pulled out to strike the housing or any members interiorly attached thereto while still being carried by the moving rotor; resistance of the compact masses of damp linters to attrition between the picker teeth and the other members of the device inevitably results in breakage of some of the pins which must be separated from the linters.

The primary object of the present invention is to provide an improved picker for fibrous materials.

2

Another object is to provide an efficient picker for fibrous material of the character of damp and compact purified cotton linters.

Other objects of the invention will appear hereinafter, the novel features and combinations being set forth in the appended claims.

Generally described, the present invention comprises a horizontal cylindrical housing or shell of noncorrosive metallic construction, provided with 10 end closures and two laterally disposed side openings. Interiorly of the housing there is provided a plurality of noncorrosive metallic bars, longitudinally positioned and secured to the housing. A picker roll of noncorrosive metallic construction 15 is axially and rotatably mounted concentrically within the housing, said roll being provided with a plurality of holes extending through its wall and having heavy pins of noncorrosive, metallic, and magnetic material extending through the 20 holes. The heavy pins are countersunk in the interior surface of the wall of said roll and radially extend so that their free ends are in juxtaposition to the metallic bars as the picker roll rotates.

25 A preferred embodiment of the invention has been chosen for purposes of illustration and description and is shown in the accompanying drawings forming a part of the specification wherein reference symbols refer to like parts wherever they occur:

30 Fig. 1 is a fragmentary front elevational view of a picker in accordance with the invention with a part of the housing cut away to show more clearly the picker roll;

35 Fig. 2 is a sectional view taken along the line line 2—2 of Fig. 1, showing the construction of the picker roll; and

40 Fig. 3 is an enlarged, fragmentary, cross-sectional view taken through the shell of the picker roll.

45 In Fig. 1 and Fig. 2, a base support 10 is provided with end sections 11. A longitudinal sheet of noncorrosive metallic material of concave cross section is supported by the base support 10 and sections 11 to form the lower or bottom housing 12 of the picker. A plurality of noncorrosive metallic bars 14 is disposed longitudinally and internally of the bottom of the housing 12 and is rigidly secured thereto. Another sheet of non-

50 corrosive metallic material of convex cross section is supported by the end sections 11 and is hingedly secured to a top member 18 which, in combination, forms the upper or top housing 15. The bottom housing 12 and top housing 15 are in 55 spaced relationship to one another so as to form

the lateral openings 16 and 17 for ingress and egress of material, respectively.

The shaft 19 is axially and concentrically disposed within the housings 12 and 15, is rotatably supported by suitable means, extends through the end sections 11, and is provided with suitable driving means. The shaft 19 supports a plurality of spiders 20, each provided with a flanged outer rim 21 of true external diameter. An outer shell 22 of heavy gage noncorrosive metallic material is drilled and countersunk as indicated at 23 and carries a plurality of radially disposed teeth or pins 24 of noncorrosive, magnetic material. The teeth or pins 24 are of heavy construction and are provided with beveled heads. These pins extend through the drilled holes 23 and are countersunk, as indicated, in the inner surface of the shell 22, with the face of the head of the pin flush with the inner surface of the shell 22 carrying the pin.

A heavy gage steel inner shell 25 is installed under the outer shell 22 to hold the pins 24 in place. Both shells 22 and 25 are secured to the spiders 20 by the use of bolts 26 of noncorrosive metallic material.

The inner shell is formed from a rectangular sheet of material curved into cylindrical form to substantially encompass the circular spiders. The outer shell is formed in a similar manner and, after drilling and countersinking and fitting with the pins, the inner shell is installed inside the outer shell. The shells are then assembled over the spiders and rigidly secured to the spiders, and the outer shell is then welded at the joint to make a continuous cylinder.

In operation, the material to be picked is fed to the picker by suitable means and enters the picker at opening 16 where it is caught by the picker roll and moved downward and forward. The material is subjected to picking and opening by opposing actions of the rapidly moving picker pins 24 and the stationary horizontal bars 14. The picked fibrous material is discharged at opening 17 to a suitable conveyer system.

In the embodiment of the invention represented in the drawings, the pins or teeth 24 are positioned in a staggered manner on a line about 30° from the direction of rotation and are grouped in a plurality of longitudinal rows spaced between the rows of bolts 26 which secure the shells 22 and 25 to the spiders 20. The pins or teeth are of chrome-steel alloy composition and are extremely hard, strong, noncorrosive, and magnetic. Teeth composed of metal having similar characteristics are suitable. Any convenient number of bars may be used in the bottom of the housing; however, it has been found that from five to seven such bars, spaced so that the clearance between the picker teeth and bars is approximately $\frac{1}{4}$ -inch, give optimum results for picking cotton linters. Other means for obtaining the projections afforded by the bars may be utilized.

The features of the picker of this invention over pickers heretofore known to the art for the purpose of picking or opening up a mass of damp, compacted cotton linters in a highly purified condition and at the same time avoid contamination of the purified linters by contact with the picker, reside in: an all metal construction, with all materials of construction which contact the linters being of noncorrosive metal, as contrasted with the part wood construction of the conventional pickers for cotton fibers; the use of picker pins of noncorrosive magnetic material and of heavy construction; the method of securing the

5 picker pins in the picker roll by countersinking the pins in the inner surface of the supporting metallic shell and backing up this shell with a metallic inner shell.

10 The picker of this invention, comprising in combination the features indicated above and others already described in connection with the explanation of the drawing, possesses a number of advantages over conventional pickers in dispersing compacted masses of damp, purified cotton linters for efficient and uniform drying in a suitable hot-air drying chamber. The use of a cylindrical picker roll of heavy construction contributes to more uniform operation due to its large amount of inertia; the use of a picker roll of all metal construction eliminates absorption of moisture, hence it remains in static and dynamic balance and operates free from vibration trouble; the use of heavy, strong picker pins minimizes bending and breakage of said pins 15 when operating against a compact mass of damp linters, which may at times offer high compressive resistance; the method of securing the picker teeth by countersinking in the inner surface of the outer shell eliminates gradual pulling of the teeth from the picker roll and consequent damage to the picker by striking the opposing longitudinal stationary bars attached to the housing while still held partially in the roll; the use of picker pins of magnetic material makes it easy 20 to remove the broken pieces of pins, which inevitably result, from the picked linters by the use of a magnetic separator; and the use of non-corrosive metallic material for all parts of the construction which contact the linters avoids 25 contamination of the linters by corrosion, or by chipping off as is encountered where wood is used.

30 What I claim and desire to protect by Letters Patent is:

40 1. An apparatus for picking a mass of damp, purified cotton linters to put it in suitable condition for efficient drying comprising in combination a closed horizontal cylindrical housing of noncorrosive metallic construction, lateral side openings positioned along the length of said housing forming inlet and outlet passages for the material to be treated, a plurality of noncorrosive metallic bars disposed longitudinally and internally of said housing and secured to the bottom thereof, and a picker roll axially and rotatably supported concentrically within said housing comprising a continuous one-piece noncorrosive metallic outer shell provided with a plurality of spaced openings having countersinks on their inner ends, a plurality of metallic picker pins 45 of noncorrosive magnetic material extending radially outward through said openings and having their inner ends countersunk therein, a metallic inner shell secured against the inner side of said outer shell and holding the metallic pins securely in the outer shell, and a plurality of metallic members of equal and true diameters mounted on a common axis and supporting both the inner shell and the outer shell.

50 2. An apparatus of the character described in claim 1 comprising means for supporting the picker roll in spaced relation in the housing so that the clearance between the ends of the picker pins and said longitudinally disposed bars is approximately $\frac{1}{4}$ inch.

55 WALTER E. SEGL.
